Patented Oct. 15, 1918.

UNITED STATES PATENT OFFICE.

VICTOR ERICKSON, OF ASTORIA, OREGON.

LOGGING-CHUTE.

1,281,919.

Specification of Letters Patent. Patented Oct. 15, 1918.

Application filed September 12, 1917. Serial No. 191,085.

To all whom it may concern:

Be it known that I, VICTOR ERICKSON, a citizen of Finland, residing at Astoria, in the county of Clatsop and State of Oregon, have invented new and useful Improvements in Logging-Chutes, of which the following is a specification.

This invention relates to conveyers, and more especially to chutes such as are used for the transfer of logs down a hill-side; and the object of the same is to provide such a chute with means for checking the progress of the logs at intervals so that they will not attain excessive speed. Retarding devices broadly speaking are now used for this purpose, consisting of what are called "goose necks" driven into the poles which form the rails of the chute and against which the traveling logs strike to retard their progress, but it frequently occurs that these devices check the movement of a log, others accumulate behind it, and a jam occurs which results in unprofitable delays, sometimes the derailment of the logs with quite disastrous results to them or surrounding objects, and always more or less loss of time of the workmen who must clear the jam.

One purpose of the present invention is to produce a retarding device which is not intended to absolutely stop the progress of the logs, but which when it does can be retracted easily from an adjacent or remote point so that the accumulation of other logs and the putting of the chute out of commission is avoided.

With this general statement of my purposes, the invention may be said to lie in the details described and claimed below and shown in the drawings wherein—

Figure 1 is a perspective view of a section of this chute, showing a single log therein as resting at its lower end against a pair of retaining devices or dogs.

Fig. 2 is an enlarged vertical longitudinal section through one of the poles of the chute at a point where the dog is mounted therein, the latter being shown in full lines in its normal position and in dotted lines as retracted to permit the log to pass on.

Fig. 3 is a perspective detail of the plate, viewed from the under side.

Fig. 4 is a perspective detail of the dog.

The chute in the present case is composed of a pair of rails standing strictly parallel, spaced such a distance as to prevent the smallest log cut from dropping between them, laid directly on the ground or on ties or other supports embedded therein, and extending from the logging field at a high altitude down the mountain side to a river or stream into which it is desired to deliver the logs, so that they can be floated onward to the mill for subsequent treatment. Each rail will by preference be made up of a number of small logs or poles P with their extremities matched and connected end to end and their inner upper sides preferably hewn off so that collectively they constitute the chute described. All this is well known to men of the craft, but is described in outline to afford basis for what follows.

At appropriate intervals along each rail, the active side of each pole is cut out or recessed as indicated at 1, and the recess continued clear through the pole in a slot 2. A metal plate 3 is then seated in the recess flush with the face thereof, the plate having a longitudinal slot 4 and carrying a cross bar or fulcrum 5 on its under side extending across the slot near the lower end of the latter. By preference the chute at each interval carries two of these plates and dogs, disposed in the poles directly opposite each other.

The dog shown in Fig. 4 has a substantially straight shank or body 10 with an eye 11 at its lower end and a head at its upper end. The head comprises a hook 12 whose bill stands at an acute angle to the length of the body, and a nib 13 projecting from the body on that side opposite said bill and at a point slightly removed from the heel of the hook, between which and the nib occurs what I will call the "face" 14 of the dog, whereas the bill of the hook might be called the "tail" thereof. The body or shank 10 of the dog extends downward through the slot 2 in the pole, and a spring 15 is employed to draw said shank normally against the upper end of the slot or against a pin 16 driven across it at a proper point. The eyes 11 of the two dogs are herein shown as connected by a cross rod 17, and a cord or rope 18 leads from the center of this rod to

a point where the workmen can grasp it. As indicated at Fig. 1 the cord may lead around a pulley 19 and uphill, and the cords of several retarding devices could be connected to a master cord 20 which when drawn upon will trip all the dogs.

In use, the hook 12 of each dog is engaged over the cross bar or fulcrum 5 of its plate, and the spring draws the parts into such position that the nib 13 stands within the upper end of the slot in said plate, the entire face 14 is exposed uphill along the chute, and the tail of the dog occupies the lower end of the slot, and therefore the elements cannot enter the slot and accumulate within the recess in the pole. When now the logs are sent down the chute, as each one strikes a retarding device which consists of a pair of these dogs, the projecting portions of the dogs bite through the bark of the log and perhaps scratch the wood thereof more or less. This depends on the distance the dogs project beyond the face of the plate 3, which is usually about one inch, and it depends also upon the size and the shape of the face 14 which may be rough, angular, or flat as shown and will be of an appropriate width—its length being about an inch as stated. Ordinarily the result will be that the progress of the log will be appreciably checked or retarded, thereby preventing it from attaining excessive speed even though it is traveling down a quite steep chute; but ordinarily also the inertia of the log will cause it to force itself past and over the retarding device, beyond which it will continue on its way at a reduced speed. Thus by placing these retarding devices at intervals along the chute, perhaps where the latter is quite steep, the engineer by the exercise of good judgment can regulate the speed of the logs being handled, and avoid the troubles enumerated above.

If, however, a log should be checked by one of these devices so that it does not run past the same as intended, the operator has only to pull on the cord which rocks the dog over its fulcrum and draws its head down into the slot in the plate, thereby withdrawing its point from within the log or its face from beneath the lower end thereof; and the log starts downward on its course, and frees those it may have accumulated in the chute above it. If a master rope 20 is employed as shown in Fig. 1, a pull thereon will trip all the dogs simultaneously and there is no necessity for the workmen passing down the chute to any particular point.

It is quite possible by using these devices to construct the chute on a rather steep hillside, where the grease usually applied to the poles or rails thereof is not needed, but the distance the dogs normally project beyond the plate may be varied according to meet these and other conditions and may be

adjusted by setting the pin 16 or by filing off the outer end of the dog to reduce the length of the face 14.

What is claimed is:

1. A logging chute composed of parallel poles laid end to end and provided at intervals with recesses and slots opening therefrom through the poles, a plate mounted in each recess and having a longitudinal slot, a fulcrum bar on the under side of the plate across the lower end of its slot, a dog having a hooked head standing within the slot in the plate and engaged with said bar and a shank standing within the slot in the pole, and yielding means for holding the dog in position to normally expose the flat face of its head toward the upper end of the chute. 70

2. A logging chute composed of parallel poles laid end to end and provided at intervals with recesses and slots opening therefrom through the poles, a plate mounted in each recess and having a longitudinal slot, a fulcrum bar across the lower end of the slot, a dog having a hooked head standing within the slot in the plate and engaged with said bar and a shank standing within the slot in the pole, a nib on the upper side of the shank remote from the point of the head leaving a face between the nib and point disposed toward the upper end of the chute, a spring moving the dog to normally expose such face above such plate, and means for swinging the dog at will in opposition to the tension of the spring. 85

3. A logging chute composed of parallel poles laid end to end and provided at intervals with recesses and slots opening therefrom through the poles, a plate mounted in each recess and having a longitudinal slot, a fulcrum bar on the under side of the plate across the lower end of its slot, a dog having a head standing within the slot in the plate and fulcrumed on said bar and a shank standing within the slot in the pole, 105 the head having a face disposed toward the upper end of the chute, a spring moving the dog to normally expose such face above such plate, a stop limiting the action of the spring, and means for swinging the dog at 110 will in opposition to the tension of the spring. 115

4. In a chute, the combination with a rail having an upright longitudinal slot, a bar across the upper end of the slot, and a pin 120 across the lower end thereof; of a dog having a hooked head fulcrumed on said bar and with its face exposed above the rail when the shank of the dog lies against said pin, yielding means for holding the dog 125 normally in this position, and manually operable devices for swinging the dog on said fulcrum, for the purpose set forth.

5. In a logging chute, the combination with a pair of spaced rails having upright 130

slots opposite each other through the rails at intervals along the chute, and a fulcrum bar across each slot; of a dog whose head is pivotally mounted on each bar and adapted to swing out of or to be housed within the slot, its shank hanging therein and provided with an eye near its lower end, a rod

connecting the eyes of opposite dogs, a cord leading from said eye whereby the dogs may be swung in one direction, and yielding ¹⁰ means for normally swinging them in the opposite direction.

In testimony whereof I affix my signature.
VICTOR ERICKSON.
